[57] CLAIM

The ornamental design for a bottle, substantially as shown and described.

DESCRIPTION

FIG. 1 is a front view of a bottle embodying my new design;

FIG. 2 is a side view thereof;

FIG. 3 is a top view thereof; and

FIG. 4 is an enlarged cross-sectional view of a portion of the bottle shown in FIG. 1 taken along the line 2—2 thereof.

Fig. 4.
